UNITED STATES PATENT OFFICE.

OTTO H. KOLB, OF PHILADELPHIA, PENNSYLVANIA.

FILLING DEVICE FOR BATTERIES AND THE LIKE.

Application filed March 5, 1921. Serial No. 449,675.

To all whom it may concern:

Be it known that I, OTTO H. KOLB, a citizen of the United States, residing at Philadelphia, in the county of Philadelphia and State of Pennsylvania, have invented certain new and useful Improvements in a Filling Device for Batteries and the like, of which the following is a specification.

My invention relates to a filling device for batteries and the like, and my invention particularly relates to improvements in filling devices used for filling storage batteries with water in sufficient quantity to bring the normal water level to the proper height above the plates within the battery.

The object of my invention is to provide a device having a liquid container which may be placed in an inverted position, resting upon the battery, having flexible tubes extending a predetermined length into the battery, which tubes will not injure the battery plates, as the weight of the container rests upon the top of the battery and not upon the plates; a further object of my invention is to provide means for shutting off the flow of water through the tube from the container during the placing of the container into position upon the battery and also when removing the same from the battery, whereby water will not be spilled over the top of the battery, and a still further object of my invention is to provide a device which is simple in construction and operation, and which can be manufactured at a low cost.

Referring to the accompanying drawing, Fig. 1, is a perspective view of my improved filling device; Fig. 2, is a side elevation of the filling device secured in a container and shown in the inverted position resting upon a battery, partly shown in section; Fig. 3, is a transverse section on line 3—3 Fig. 2; Fig. 4, is a vertical section on line 4—4 Fig. 3; Fig. 5, is a side elevation of a different form of stopper having finger recesses formed on opposite sides thereof for impinging the tubes, and Fig. 6 is a transverse section on line 6—6 Fig. 5.

In the accompanying drawings, in which like reference characters refer to like parts; 1 represents the stopper having a body portion 2 adapted to be tightly fitted into the mouth 3 of a container 4. The stopper 7 is provided with a head portion 6 connected with the body portion 2 by a connecting member 7, which latter is a sufficient length

to permit the stopper having a recess 9, formed in the side thereof, of sufficient dimensions so that a finger may be placed therein and compress either of the tubes 12 and 13 extending longitudinally through the stopper.

The tubes 12 and 13 are sealed, or tightly fitted, into the apertures formed through the body portion 2 of the stopper, to prevent air entering the container 4 around said tubes.

The connecting member 7 of the stopper is provided with a lug 15 positioned opposite to the finger recess 9. Said lug 15 forms a ridge over which the tubes are slightly curved, as shown in Fig. 4, and against which the tubes may be more readily compressed by the finger to close the passageway through the tubes and thus shut off the flow of air or liquid through the same.

The head portion 6 of the stopper is adapted to rest upon the flange 16 formed on the top of the storage battery 17, and support the container 4 in an inverted position with the ends of the tubes 12 and 13 extending through the filling opening 18 of the battery. The end surface of the head 6 is provided with radial grooves 20 to allow air to pass between the head and the battery flange 16.

The water tube 13 is cut off the proper length beyond the head 6, so that the end of said tube will just touch the plates 22 of the battery and the air tube 12 is then cut as much shorter than the water tube 13 as it is desired to have the water level normally maintained above the plates.

Figs. 5 and 6, show a modified form of the stopper in which recesses 25 and 26 are formed opposite each other and extending through the stopper, exposing the tubes from either side of the stopper, thus permitting the tubes to be compressed between two fingers, which may readily be inserted into said recesses. The head portion is connected with the body portion by two connecting members 28 and 29.

The tubes 12 and 13 are made of rubber which will not be injured by the acid in the battery and the tubes have sufficient flexibility so that they will not break the battery plates or otherwise injure the battery.

The operation of my invention is as follows: The receptacle is filled with water and the stopper tightly inserted therein; a fin-

ger is placed up one or both of the tubes to shut off the flow of air or water through the tubes and the receptacle can then be inverted and placed on the top of the battery with the tubes extending into the filling opening; the finger is then removed and air enters the receptacle from the battery through the shorter tube which permits the water to flow through the longer tube until 10 the level of the liquid in the battery seals the mouth of the air tube. The fingers are again placed upon the tubes to prevent the water from dripping over the battery when the container is being removed from the 15 battery.

Having thus described my invention I claim and desire to secure by Letters Patent:

1. A filling device comprising a stopper having a body portion, a head portion, a 20 connecting member between the body portion and the head portion, flexible tubes extending through the said body portion and the head portion and projecting predetermined lengths beyond the head portion, 25 whereby the head portion will limit the distance the tubes may be inserted into a receptacle, and said connecting member being constructed to permit the tubes to be compressed between the said body and head 30 portions.

2. A battery filling device comprising a stopper adapted to be fitted into a liquid container, said stopper having a portion thereon adapted to rest upon a battery adjacent to the filling aperture formed therein, a tube extending through the stopper for the passage of air into the container and adapted to extend into the battery aperture and terminate at the normal liquid

level of the battery, a second tube extending through the stopper for the passage of liquid into the battery and terminating below the said normal liquid level, and said last mentioned tube being made of flexible material so as not to injure the interior of 45 the battery.

3. A battery filling device comprising a stopper adapted to be fitted into a container, tubes extending through the stopper for the passage of air and liquid and adapted to be inserted into the filling aperture of a battery, said stopper having a portion adapted to rest upon the outside of the battery to limit the distance the said tubes may be inserted into the battery and said tubes being made of flexible material so as 55 not to injure the battery plates.

4. A filling device comprising a container for holding a supply of liquid, tubes for the passage of air and liquid to and from the container, a member upon the container located adjacent to the said tubes forming a rest for supporting the container upon the top of a receptacle having a filling aperture formed therein, said tubes extending 60 a predetermined length beyond the supporting surface of the said rest member to limit the distance the tubes may extend through the said aperture into the receptacle, and said member having an open portion formed 65 therein exposing a portion of the tubes whereby the tubes may be compressed at a point between the container and the rest end of the said member to shut off the flow of liquid.

In testimony whereof I affix my signature.

OTTO H. KOLB.
